(57) CLAIM

The ornamental design for a table, as shown and described.

DESCRIPTION

FIG. 1 is a perspective view of a first embodiment of a table showing our new design;

FIG. 2 is a top plan view thereof;

FIG. 3 is a front elevation view thereof;

FIG. 4 is a right side elevation view thereof, the left side being a mirror image;

FIG. 5 is a rear elevation view thereof;

FIG. 6 is an enlarged fragment of a portion of the table shown in FIG. 1 and labeled 6;

FIG. 7 is an enlarged fragment of a portion of the table shown in FIG. 1 and labeled 7;

FIG. 8 is perspective view of a second embodiment of a table showing our new design;

FIG. 9 is a top plan view thereof;

FIG. 10 is a front elevation view thereof;

FIG. 11 is a right side elevation view thereof, the left side being a mirror image;

FIG. 12 is a rear elevation view thereof;

FIG. 13 is an enlarged fragment of a portion of the table shown in FIG. 8 and labeled 13; and,

FIG. 14 is an enlarged fragment of a portion of the table shown in FIG. 8 and labeled 14.

The broken lines show environmental subject matter and form no part of the claimed design. The fragmentary showing of wood grain in FIGS. 1-5 and 8-12 and shown in detail in FIGS. 6, 7, 13, and 14 is understood to be repeated throughout the surfaces shown. The second embodiment is shown with symbolic breaks in length in FIGS. 8-10 and 12, and those portions of the article between the break lines form no part of the claimed design.

1 Claim, 14 Drawing Sheets
